UNITED STATES PATENT OFFICE.

EDWARD ROWE, OF INDIANA, PENNSYLVANIA.

RAIN-WATER CUT-OFF AND STRAINER.

SPECIFICATION forming part of Letters Patent No. 358,820, dated March 1, 1887.

Application filed June 30, 1886 Serial No. 206,733. (No model.)

To all whom it may concern:

Be it known that I, EDWARD ROWE, a citizen of the United States, residing at Indiana, in the county of Indiana and State of Pennsylvania, have invented certain new and useful Improvements in Rain-Water Cut-Offs and Strainers; and I do declare the following to be a full, clear, and exact description of the invention, such as will enable others skilled in the art to which it appertains to make and use the same, reference being had to the accompanying drawings, and to letters or figures of reference marked thereon, which form a part of this specification.

Figure 1 of the drawings is a representation of this invention, and is a vertical section. Fig. 2 is a top view of the elliptical receiving-chamber.

My invention relates to rain-water cut-offs and strainers; and it consists in the construction and novel combination of parts, as hereinafter described, and pointed out in the claim.

The object of this device is to divert rain-water from a roof from one conductor to another, and is used mainly to run the first water of a shower, which is generally dirty, into the sewer, after which the clean water is directed into the cistern or other receptacle.

Referring by letter to the accompanying drawings, A designates the upper portion of the rain-water spout, which is connected at its upper end to the eaves-trough in the ordinary manner, and extends down to within a proper distance of the ground, where it enters or extends a short distance into the slightly-enlarged upper end of a lower section, B, of spout, which is hinged at one side to the lower end of the upper section, A, and is provided on its outside, near its upper end, with a gravity-weight, C, which tends to hold the said lower section, B, normally in line with the upper section, A, of the spout.

The lower section, B, is provided, a short distance below the gravity-weight C, with an eye, D, to which the upper end of a controlling chain, wire, or cord, or movable rod, E, is secured, the lower end of said cord E being connected to a nail or the like, so that it can be readily reached by a person inside the building from the window or a door of the building, so that it will be unnecessary to go out in the rain to operate the cut-off.

The lower end of the hinged or swinging section B of the pipe or spout extends into the open upper end of an elliptical receiving-chamber, G, having two discharge pipes or nozzles, G' and G'', at its lower end, one, G', leading to the sewer and the other, G'', leading into the cistern or other rain-water receptacle. The receiving-chamber G is provided with a short vertical partition, H, which rises from the bridge between the two discharge pipes or nozzles G' and G'', and extending from this portion H, over the discharge leading to the cistern, is a screen, I, which is of wire or perforated sheet metal. This screen I is slightly inclined toward the open discharge-pipe G'', so that any dirt that may fall upon it will be carried down said incline, and will pass out through the open discharge-pipe after the water has been directed upon the screen, thereby causing or permitting only clean water to enter the cistern. After the roof has been washed free from dirt the chain, cord, or wire may be tied in a loose condition, so that it will permit the hinged section to hang in its normal position and convey the rain-water to the cistern or other receptacle without further attention on the part of the operator. The lower section of spout or pipe should be large enough at its upper end and small enough at its lower end to work easily.

After the rain has ceased to fall from the roof the cord may be again drawn upon to direct the hinged pipe to the sewer, or at any time, should it be necessary, this may be done.

Having described this invention, what I claim, and desire to secure by Letters Patent, is—

The combination, with the rain-water spout, of the hinged controlling-pipe weighted on the side opposite the hinge, the operating-cord, and the receptacle G, provided with the discharge G' G'', the vertical partition H, and the screen I, connected to the inner wall of the receptacle G, and resting on the vertical partition H, substantially as specified.

In testimony whereof I affix my signature in presence of two witnesses.

EDWARD ROWE.
